UNITED STATES PATENT OFFICE

ELMER L. JOHNSON, OF CELORON, NEW YORK

DESIGN FOR A COMBINATION PEN HOLDER AND ASH TRAY

Application filed March 13, 1930. Serial No. 34,843. Term of patent 7 years.

To all whom it may concern:

Be it known that I, ELMER L. JOHNSON, a citizen of the United States, residing at Celoron in the county of Chautauqua and State of New York, have invented a new, original, and ornamental Design for a Combination Penholder and Ash Tray, of which the following is a specification, reference being had to the accompanying drawing, forming part thereof.

The figure is a perspective view of the combination pen holder and ash tray showing my new design.

I claim:

The ornamental design for a combination pen holder and ash tray as shown.

ELMER L. JOHNSON.
